FRANK J. NIES, OF GLEN RIDGE, NEW JERSEY, ASSIGNOR TO THE PEELLE COMPANY,
OF BROOKLYN, NEW YORK, A CORPORATION OF NEW YORK

CANOPY-TYPE DOOR

Application filed October 2, 1929. Serial No. 396,788.

My invention relates to canopy type doors, and more particularly to a door of this type embodying therein a combined guiding and safety attachment by which the lower edge 5 of the lower, foldable section of the door is guided during the opening and closing movements of the door, and, in the event of breakage of the chains or other flexible connections controlling the opening and closing 10 movements of the door, the falling of the door is prevented.

The so-called canopy type door or "jack-knife" door as it is sometimes called, consists of two sections, the upper one of which 15 is hinged above and adjacent the lintel of the door opening, and the lower one of which is hinged at the meeting line of the two sections.

Adjacent the jambs of a door opening, vertically extending wall angles are customarily used, and the lower section is provided with arbors at opposite edges, adjacent the bottom thereof upon which are mounted rollers which bear against such wall angles. Such arbors 25 also carry swivelling fittings to which flexible connections are attached, these connections passing over pulleys above the wall angles, and being connected with a counterweight, or an operator, for facilitating the opening 30 and closing of the door.

When a door of the type above referred to is being opened, the two sections fold toward each other, the lower edge of the lower section moving in a substantially vertical line 35 by reason of the action of the counterweight or the operator and of the swivelling fitting, and the location of the various guide pulleys, the thrust of the upper section and the point 40 of the attachment of the flexible connections serving to engage the rollers at opposite edges of the lower section with the wall angles at all times during both the opening and closing of the door, and while the door is in the open position.

Heretofore, canopy type doors have been made and successfully operated, in which the wall angles each carried a rack bar, and the pivotal fitting for the flexible connections 50 carried a ratchet tooth or dog acted upon by a spring so as to engage the tooth or dog

with the rack bar in the event of the breakage of a chain. Such doors, in respects other than the safety feature above referred to, embodied all of the other characteristics common to doors of this type, including the rollers co-acting with the angle bars for permitting ease of movement when opening and closing a door.

Doors of the type to which my invention relates are extensively used for closing the platform entrances of warehouses and similar structures, such entrances ordinarily being both wide and high. By reason of the dimensions of the door sections, and the necessity for constructing them to withstand the severe treatment to which they are subjected, considerable weight is required in the doors and serious injury may result to workers in the event of the breakage of the flexible connections. While the rack and ratchet mechanism above referred to, offers a safeguard against the accidental falling of the doors, due to breakage of the connections, there is a possibility of the breakage of the safety 75 attachment, due to the sudden application of the full load of the door to the parts of the attachment and a slight acquired momentum before the ratchet or dog is properly engaged with one of the teeth of the rack bar.

In a canopy type door embodying my invention, I provide an attachment adjacent the bottom edge of the lower door section, which, under normal conditions, co-operates with the guide structure to prevent any substantial movement of this section, or of the door in its entirety, towards or from the wall of the building, the various parts of which attachment, in the event of the breakage of the flexible connections, co-acting to develop a progressively increasing force resisting downward movement of the door. The fitting, in its entirety, including the various guiding and braking members, is pivotally connected with the lower door section permitting the necessary turning or swivelling movement of said section during the opening and closing of the door. Said swivelling movement, however, will not disturb the operative relation of the different parts of the attachment to each 95 100

other, and the co-operating parts of the guide structure.

I embody in the attachment a brake member co-operating with the guide structure and one of the guide rollers to ensure under normal conditions against movement of the lower edge of the lower door section toward or away from a door opening, and in the event of breakage of the flexible connections, 10 to develop the desired braking action to prevent violent closing of the door. This brake member and its support, are so constructed as to be quickly set through a spring, which is held under tension by the weight of the door, and ensures a substantially instantaneous initial setting of the safety device following the breakage of a connection. The construction, however, is such that after such initial setting, the brake member may receive 15 additional movement, due to the movement and weight of the door, which will develop progressively increasing braking power, thus relieving the guide structure from all those stresses resulting from the sudden stoppage of the door, and at the same time preventing the development of sufficient momentum to subject this guide structure to excessive stresses.

Furthermore, in the event of the breakage 20 of the flexible connections, the whole attachment, even though the spring actuating the brake member should break, will swivel about its connection with the door in a manner to engage the brake member with the co-operating portion of the guide structure and cause the ultimate setting of the brake member and thus retard, if not entirely stop, the closing movement of the door. In fact, even in the event of the partial failure of the brake mechanism, it will have a retardant action which will ensure movement of the door at a sufficiently low speed to enable workers to escape from the danger zone, and avoid serious injury to any one who might be struck by the door while it is thus slowly moving.

The invention consists primarily in a canopy type door embodying therein vertically extending guides upon opposite sides of the door opening, including metallic flanges projecting toward each other, a door section between said guides, a combined guiding and braking attachment at each side of said panel including therein a frame, a pivotal connection between said frame and said door section, a guide roller concentric with said pivotal connection and engaging one face of the flange of a guide structure, an eccentric brake member rotatably mounted in said frame in engageable relation with the opposite face of the flange of a guide structure, a lever carried by and movable with said brake member, a link slidably mounted in said frame, and connections between said link and said lever, guide pulleys above said

guide structures respectively, and flexible connections for sustaining the load of said door section connected with the links of said attachment and passing about said pulleys; and in such other novel features of construction and combination of parts, as are hereinafter set forth and described, and more particularly pointed out in the claims hereto appended.

Referring to the drawings,

Fig. 1 is a condensed view from the floor side of the door opening, of a canopy type door embodying the invention;

Fig. 2 is a side view thereof with the guide structure partly broken away;

Fig. 3 is a horizontal section of the lower portion of the lower door section;

Fig. 4 is a view of the combined guide and brake attachment shown in relation to the guide structure, which is shown in vertical section;

Fig. 5 is a view similar to Fig. 1 from the opposite side of the attachment; and

Fig. 6 is a view from the left of Fig. 4 with the rail structure partly broken away.

Like numerals refer to like parts throughout the several views.

In the embodiment of the invention shown in the drawings, I have illustrated it in connection with a canopy type door consisting of an upper section 10, hinged to the wall of a building above the lintel of a door opening, shown at 11, so as to fold upwardly and away from said wall, and a lower door section 12 hinged to the upper door section by means of hinges 13 as shown in Fig. 2, so as to fold toward said upper section when the door is being opened.

My invention does not relate to any of the details of construction of the door sections and the manner of mounting and connecting same as shown in the drawings, but merely to the use with a door section having an upwardly sliding and swinging movement of combined braking and guiding attachments carried by this door section and co-operating with the guide structures therefor.

Adjacent each jamb of the door opening 11 is a guide structure which, in the form of the invention shown, comprises a wall angle 14 secured in any desired manner to the wall of a building, and carrying a guide angle 15, one flange 16 of which extends toward the guide structure adjacent the other door jamb. The door proper is located between the flanges of said guide angles, and is spaced therefrom sufficiently to provide clearance for the combined guiding and braking attachment located at each side of the lower section of the door shown in the drawings.

The construction of each combined guiding and braking attachment is the same as the other, so that a detailed description of but one of them is necessary. This attachment comprises a substantially triangular

frame 17, mounted upon a bearing stud 18 carried by a bracket 19 firmly secured to one face of the door section 12 so as to have a swivelling relation to the said door section 5 and thus permit that turning action of the door incidental to the opening and closing movements thereof. The attachment also includes a guide roller 20, mounted upon the bearing stud 18, thus being concentric with 10 the pivotal connection between the frame 17 and the door. This guide roller is of a diameter to be maintained in engaging relation to the flange 16 of the guide angle 15.

Rotatably mounted in the frame 17 is an 15 eccentric brake member 21, in engageable relation with the face of the flange 16 opposite to that engaged by the roller 20. This brake member 21 is carried by a shaft 22, mounted in bearings in said frame 17, and is 20 located at one side of this frame, said shaft 22 upon the other side of said frame being provided with a lever having one arm 23, to which is connected one end of a spring 24, the other end of which is connected with a 25 pin 25, carried by the frame 17. The normal tendency of this spring is to so rotate the shaft 22 and the brake member 21 as to engage the latter with the face of the flange 16 with sufficient force to cause frictional 30 engagement of these parts and develop braking action in a manner to be hereinafter described. The other arm 26 of said lever is connected in any desired manner, as by a wire cable 27, with a pin 28 carried by links 35 29 and 30 upon opposite sides of, and extending above, the frame 17.

The links 29 and 30 are vertically slidable 40 in relation to the frame 17, so that with upward movement of said links, the lever 23—26 will be oscillated in a manner to tension the spring 24, and at the same time turn the shaft 22 to an extent to disengage the eccentric brake member 21 from the face of the flange 16.

Connected with the upper end of the links 45 29 and 30 in any desired manner, is a flexible connection for sustaining the load of the door during the opening and closing movement. There being one such combined guiding and braking attachment at each side of the door, there are two such flexible connections, indicated respectively at 31 and 32, one of these connections, as 31, passing over guide pulleys 33 and 34, and the other, as 32, 50 passing over a guide pulley 35. The other ends of these connections 31—32 are, in the form of the invention shown, attached to a counterweight 36.

The movement of the links 29 and 30 in relation to the frame 17 is limited by a bolt 37 55 secured to said links and passing through an elongated slot 38 in the upper portion of the frame 17. Also connecting said links is a pin 39 to facilitate the attachment of a flexible connection 31 or 32 with the links in any

desired manner, as by means of a shackle 40 which also serves as a spacer to prevent binding of said links against the sides of the frame 17.

Mounted upon the bolt 37 is a supplemental guide roller 41, in engaging relation with the same face of the flange 16 with which the brake member 21 co-operates. The slot 38 is preferably extending at an angle downwardly away from the flange 16, so as to cause the roller 41 to have movement away from the said flange with downward movement of the links 29 and 30 in the event of the breakage of the flexible connections 31 or 32.

By the use of the supplemental guide roller 41, all possibility of movement of the frame 17, sufficient to engage the brake member 21 with the flange 16, is prevented during the normal operation of the door.

The operation of the herein described door is substantially as follows:—

With the door in the closed position, the load of the counterweight 36 raises the links 29 and 30 to their uppermost position, until the bolt 37 carried thereby engages the top of the slot 38. This positioning of the links acts upon the arm 26 of the lever carried by the shaft 22 in a manner to develop and maintain tension in the spring 24, and at the same time so turn the brake member 21 as to maintain it out of engagement with the face of the flange 16 with which it co-operates. This position of parts is clearly shown in Figs. 4 and 5 of the drawings.

So long as a door is functioning normally, the relation of parts above described will continue, and when opening or closing a door, the frame 17 and the parts carried thereby have a directly vertical rise and fall without any change in the relative position of the parts.

The guide roller 20, during the opening and closing of the door, by engagement with one face of the flange 16, and the roller 41, by engagement with the other face of said flange, maintains this position of the frame at all times during the normal functioning of the door. Furthermore, the brake member 21 co-operates with the roller 41 to the extent of positively preventing excessive inward movement of the door as a result of the impacts thereon from the side of the door positioned toward the door opening.

As the lower section 12 rises or falls, the bracket 19 and its bearing stud 18 may turn freely in relation to the frame 17, thus permitting the necessary turning action of the door incidental to its operation, notwithstanding the direct vertical movement of the frame 17 to which power is applied either by the counterweight 36, or other desired means for facilitating the opening or permitting the closing of the door.

With the exception of the guiding action of the attachment as above described, the normal operation of the door is the same as that of the ordinary canopy, or related, type of door.

The main purpose of the attachment, however, is to guard against possible injury to workmen, or to the door structure, resulting from the falling of the door because of the failure of the counterweight or other means acting through the frame 17 to properly sustain the load of the door.

Assuming that the counterweight 36 is disconnected from the chains or other flexible connections 31 and 32, the door is free to close by gravity. Immediately, however, that said connections 31 and 32 are relieved of the load of the counterweight, the spring 24 acts upon the arm 23 of the lever connected with the shaft 22, to turn said shaft, and with it the eccentric braking member 21.

This turning movement of said lever, through the flexible connection 27 and pin 28, draws the links 29 and 30 downwardly, since such movement of these links is permitted by the release of the chain 31 and 32 from the load of the door and of the counterweight.

The turning of the eccentric braking member 21 engages this member with the face of the flange 16 with which it co-operates, so that downward movement of the frame 17 with the door, will firmly clamp said flange between the braking member 21 and the guide roller 20.

Following the initial frictional engagement of the member 21 with the flange 16, the load of the door imparts further rotary movement to the member 21, thus developing a braking action commensurate with the weight and speed of the door. By this is meant that if, for any reason, the door should acquire some momentum, this is utilized to develop braking action.

A desirable characteristic in the action of the braking member 21 is that it accomplishes a rapid but gradual stoppage of the door, thus minimizing the strains to which the fitting and the guide structure are necessarily subjected when stopping the door.

With the freeing of the links 29 and 30, there may be a slight tendency of the frame 17 to turn about the bearing stud 18. This is not undesirable, since it merely results in assisting to bring the braking member 21 into engagement with the flange 16, and any engagement of said braking member with said flange will impart to the said member a rotary movement resulting in the development of the desired clamping and braking action. In fact, this movement of the frame 17 will, in the event of the breakage of the spring 24, result in a delayed braking action. Under this condition, it is possible that the door might not be entirely stopped until

after it has had considerable movement, but during this movement the braking action developed retards the movement of the door, so that even if it did strike somebody or some object, no injury would be inflicted, or would be of a minor character.

It will be borne in mind that the door section itself and the bearing stud 18 carried thereby are free to have a small quantity of movement away from the wall about the door opening 11.

The roller 41 is used mainly to prevent such movement of the frame 17, during the normal operation of the door, as will engage the braking member 21 with the flange 16, being a stop member for accurately defining the position of the frame 17 during the normal operation of the door.

While the braking member 21 is shown as a disk, it is obvious that merely the lower 180° of this disk are operative, the use of the disk being merely for the purpose of permitting the reversal of the braking member in the event of wear, and simplifying the production of the combined guiding and braking attachment.

During the opening and closing of the door, there is a thrust of the bearing stud 18 toward the flange 16, due to the angular position of the door section 12, throughout the major portion of such opening and closing movements, and the guide roller 20 is relied upon mainly to ensure the vertical movement of the frame 17 and of the lower portion of the door section 12, which, however, has a swivelling movement about the axis of the guide roller 20 during this vertical movement.

The inclined slot 38 in the upper portion of the frame 17 causes the roller 41 to move away from the flange 16 with any downward movement of the links 29 and 30. This is merely to avoid possible binding of the bolt 37 when conditions are such as to require downward movement of the links 29 and 30.

The braking member 21 may be of a friction metal, or of any other desired material possessing sufficient strength for the purpose for which it is used. The frame 17 and links 29 and 30 may be of malleable iron. The strength of the spring 24 need be merely sufficiently great to ensure a rapid movement of the lever carrying the shaft 22 and the braking member 21, since under normal circumstances this lever does not carry any of the load of the door as the bolt 37 is engaged with the top of the slot 38.

It is not my intention to limit the invention to the precise details of construction shown in the drawings, it being obvious that such may be varied without departing from the spirit and scope of the invention.

It will be noted however, that the invention involves the use of a particular guide structure, and a type of door in which the

section carrying the combined guide and brake attachment has both vertical and turning movement when opening and closing the door.

5 Having described the invention, what I claim as new and desire to have protected by Letters Patent, is:—

1. A canopy type door embodying therein vertically extending guides upon opposite 10 sides of the door opening, including metallic flanges projecting toward each other, a door section between said guides, a combined guiding and braking attachment at each side of said panel including therein a frame, a pivotal connection between said frame and said door section, a guide roller concentric with said pivotal connection and engaging one face of the flange of a guide structure, an eccentric brake member rotatably mounted in 15 said frame in engageable relation with the opposite face of the flange of a guide structure, a lever carried by and movable with said brake member, a link slidably mounted in said frame, and connections between said link and said lever, guide pulleys above said guide structures respectively, and flexible connections for sustaining the load of said door section connected with the links of said attachment and passing about said pulleys. 20
2. A canopy type door embodying therein vertically extending guides upon opposite sides of the door opening, including metallic flanges projecting toward each other, a door section between said guides, a combined guiding and braking attachment at each side of said panel including therein a frame, a pivotal connection between said frame and said door section, a guide roller concentric with said pivotal connection and engaging one 25 face of the flange of a guide structure, an eccentric brake member rotatably mounted in said frame in engageable relation with the opposite face of the flange of a guide structure, a lever carried by and movable with said brake member, a link slidably mounted in 30 said frame, a spring connected with said frame and acting upon one arm of said lever, connections between the other arm of said lever and said link, and means co-operating with the same face of the flange engageable by said brake member for limiting the oscillatory movement of said frame in one direction, guide pulleys above said guide structures respectively, and flexible connections for sustaining the load of said door section connected with the links of said attachment and passing about said pulleys. 35
3. A canopy type door embodying therein vertically extending guides upon opposite sides of the door opening, including metallic flanges projecting toward each other, a door section between said guides, a combined guiding and braking attachment at each side of said panel including therein a frame, a pivotal connection between said frame and said door section, a guide roller concentric with said pivotal connection and engaging one 40 face of the flange of a guide structure, an eccentric brake member rotatably mounted in said frame in engageable relation with the opposite face of the flange of a guide structure, a lever carried by and movable with said brake member, a link slidably mounted in 45 said frame, a spring connected with said frame and acting upon one arm of said lever, and connections between the other arm of said lever and said link, guide pulleys above said guide structures respectively, and flexible connections for sustaining the load of said door section connected with the links of said attachment and passing about said pulleys. 50
4. A canopy type door embodying therein vertically extending guides upon opposite sides of the door opening, including metallic flanges projecting toward each other, a door section between said guides, a combined guiding and braking attachment at each side of said panel including therein a frame, a pivotal connection between said frame and said door section, a guide roller concentric with said pivotal connection and engaging one 55 face of the flange of a guide structure, an eccentric brake member rotatably mounted in said frame in engageable relation with the opposite face of the flange of a guide structure, a lever carried by and movable with said brake member, a link slidably mounted in said frame, connections between said link and said lever, and means co-operating with the same face of the flange engageable by said brake member for limiting the oscillatory movement of said frame in one direction, guide pulleys above said guide structures respectively, and flexible connections for sustaining the load of said door section connected with the links of said attachment and passing about said pulleys. 60
5. A canopy type door embodying therein vertically extending guides upon opposite sides of the door opening, including metallic flanges projecting toward each other, a door section between said guides, a combined guiding and braking attachment at each side of said panel including therein a frame, having a substantially vertically extending slot adjacent the top thereof, a pivotal connection between the lower portion of said frame and said door section, a guide roller concentric with said pivotal connection and engaging one 65 face of the flange of a guide structure, an eccentric brake member rotatably mounted in said frame adjacent said guide roller and in engageable relation with the opposite face of the flange of a guide structure, a lever carried by and movable with said brake member, a link, a bolt carried by said link and passing through the slot in said frame, and connections between said link and said lever, guide pulleys above said guide structures respectively, and flexible connections for sustaining the load of said door section connected with the links of said attachment and passing about said pulleys. 70

taining the load of said door section connected with the links of said attachment and passing about said pulleys.

6. A canopy type door embodying therein vertically extending guides upon opposite sides of the door opening, including metallic flanges projecting toward each other, a door section between said guides, a combined guiding and braking attachment at each side of said panel including therein a frame, having a substantially vertically extending slot adjacent the top thereof, a pivotal connection between the lower portion of said frame and said door section, a guide roller concentric with said pivotal connection and engaging one face of the flange of a guide structure, an eccentric brake member rotatably mounted in said frame adjacent said guide roller and in engageable relation with the opposite face of the flange of a guide structure, a lever carried by and movable with said brake member, a link, a bolt carried by said link and passing through the slot in said frame, a spring connected with said frame and acting upon one arm of said lever, and connections between the other arm of said lever and said link, guide pulleys above said guide structures respectively, and flexible connections for sustaining the load of said door section connected with the links of said attachment and passing about said pulleys.

7. A canopy type door embodying therein vertically extending guides upon opposite sides of the door opening, including metallic flanges projecting toward each other, a door section between said guides, a combined guiding and braking attachment at each side of said panel including therein a frame, having a substantially vertically extending slot adjacent the top thereof, a pivotal connection between the lower portion of said frame and said door section, a guide roller concentric with said pivotal connection and engaging one face of the flange of a guide structure, an eccentric brake member rotatably mounted in said frame adjacent said guide roller and in engageable relation with the opposite face of the flange of a guide structure, a lever carried by and movable with said brake member, a link, a bolt carried by said link and passing through the slot in said frame, connections between said link and said lever, and a supplemental guide roller mounted upon said bolt and co-operating with the same face of the flange engageable by said brake member for limiting the oscillatory movement of said frame in one direction, guide pulleys above said guide structures respectively, and flexible connections for sustaining the load of said door section connected with the links of said attachment and passing about said pulleys.

8. A canopy type door embodying therein vertically extending guides upon opposite sides of the door opening, including metallic

flanges projecting toward each other, a door section between said guides, a combined guiding and braking attachment at each side of said panel including therein a frame, having a substantially vertically extending slot adjacent the top thereof, a pivotal connection between the lower portion of said frame and said door section, a guide roller concentric with said pivotal connection and engaging one face of the flange of a guide structure, an eccentric brake member rotatably mounted in said frame adjacent said guide roller and in engageable relation with the opposite face of the flange of a guide structure, a lever carried by and movable with said brake member, a link, a bolt carried by said link and passing through the slot in said frame, a spring connected with said frame and acting upon one arm of said lever, connections between the other arm of said lever and said link, and a supplemental guide roller mounted upon said bolt and co-operating with the same face of the flange engageable by said brake member for limiting the oscillatory movement of said frame in one direction, guide pulleys above said guide structures respectively, and flexible connections for sustaining the load of said door section connected with the links of said attachment and passing about said pulleys.

9. A canopy type door embodying therein vertically extending guides upon opposite sides of the door opening, including metallic flanges projecting toward each other, a door section between said guides, a combined guiding and braking attachment at each side of said panel including therein a frame, a pivotal connection between said frame and said door section, a guide roller engaging one face of the flange of a guide structure, an eccentric brake member rotatably mounted in said frame in engageable relation with the opposite face of the flange of a guide structure, a member engageable with and slidable upon said frame toward and from said brake member, means for imparting rotary movement to said brake member, and connections between said member and said means, guide pulleys above said guide structures respectively, and flexible connections for sustaining the load of said door section connected with said member and passing about said pulleys.

In witness whereof I have hereunto affixed my signature this 28th day of September, 1929.

FRANK J. NIES.
